UNITED STATES PATENT OFFICE.

FRED ANDREWS, OF CHICAGO, ILLINOIS, ASSIGNOR OF ONE-HALF TO THE ELEVATOR SUPPLY AND REPAIR COMPANY, OF SAME PLACE.

ELECTRIC SWITCH OR SIGNAL APPARATUS.

SPECIFICATION forming part of Letters Patent No. 634,226, dated October 3, 1899.

Application filed September 3, 1898. Serial No. 690,173. (No model.)

To all whom it may concern:

Be it known that I, FRED ANDREWS, a resident of Chicago, in the county of Cook and State of Illinois, have invented certain new 5 and useful Improvements in Electric Switch and Signal Apparatus, of which I do declare the following to be a full, clear, and exact description.

The present invention has for its object, 10 first, to provide an improved construction of electric switch more especially adapted for use in connection with signal systems for passenger-elevators, although susceptible of use in other situations, and, second, to improve in 15 other respects signal apparatus for use in passenger-elevators.

The invention consists in the novel mechanism hereinafter described, illustrated in the accompanying drawings, and particularly 20 pointed out in the claims at the end of this specification.

Figure 1 is a diagrammatic view through the elevator-shafts of a building, showing elevators with my improvements applied thereto. 25 Fig. 2 is an enlarged detail view in side elevation of the switch mechanism. Fig. 3 is a view in cross-section on line 3 3 of Fig. 2. Fig. 4 is a detail view, in vertical section, through the upper half of the mechanism 30 shown in Fig. 2. Fig. 5 is a view in front elevation through the push-button box, the cover of the box and the push-buttons being removed. Fig. 6 is a view on line 6 6 of Fig. 7. Fig. 7 is a view in section on line 7 7 of Fig. 35 5, looking in the direction of the arrows. Fig. 8 is a view similar to Fig. 1, but showing a modified construction of apparatus. Fig. 9 is a view similar to Fig. 2, showing a modified construction of switch mechanism. Fig. 10 40 is a view in section on line 10 10 of Fig. 9, looking in the direction of the arrows.

Referring more particularly to the constructions shown in Figs. 1 to 4 of the drawings, A and A' denote two adjoining elevator-shafts of a building, the floors of the building 45 through which the shafts pass being designated as 1, 2, 3, and 4, respectively.

B and B' denote the elevator-cars. To each of the cars B and B' is connected a lifting-cable B², that passes around an overhead 50 pulley B³ to the usual winding-drum. (Not

shown.) Upon the shaft of the pulley B³ is mounted the sprocket-wheel X, connected by a chain X' to a similar sprocket-wheel X². The wheel X² is carried upon a shaft x, upon 55 which is mounted a sprocket-wheel X³, over which passes a chain Y, to which is connected a depending rod or cable Y'. While the rod or cable Y' and the mechanism for shifting the same correspond with the indicator-rod 60 and shifting mechanism shown in Letters Patent No. 511,987, granted to me January 2, 1894, it is manifest that the mechanism for shifting the cable Y' from the pulley-shaft may be the same as that shown in my above- 65 mentioned patent, or any other convenient mechanism may be employed for shifting the cable Y', and a rod or wire may be used instead of a cable, if preferred.

It will be understood, of course, that the 70 mechanism for shifting the rod or cable Y' serves as a reducing mechanism, so that while the shift of this cable corresponds to the travel of the elevator-car, but a very slight movement of the cable occurs. 75

Within the elevator-cars B and B' are arranged, respectively, the incandescent electric signal-lamps b and b', the purpose of which lamps is to notify the operators of the car that a passenger is awaiting the service 80 of the car upon one or other of the floors.

The mechanism next to be described is so designed that a passenger upon any floor by operating the push-button can cause the lamps within the cars to begin to burn as the cars 85 approach the floor on which the passenger is standing in order that the operator of any car approaching the floor will be notified by the lighting of the lamp that a passenger is awaiting service at such floor. Thus, for example, if the passenger upon the third floor 90 is desirous of going up he will push the "up" button at such floor and will cause the signal-light within each car that approaches the floor in upward direction to burn, the lamp 95 remaining lighted until after the car passes the floor on which the signal was given.

At convenient points adjacent the elevator-shaft are arranged the switches C, and at each floor of the building is arranged one or more 100 push-button boxes D. Where there are but a few elevator-shafts in close proximity, a

single push-button box at each floor will suffice. Each switch may be so constructed as to serve for several floors of the building, or, if preferred, a switch may be located at each 5 floor of the building. The construction illustrated in Figs. 1 to 4 of the drawings shows each switch adapted for controlling the signals from two adjoining floors.

Each switch C (in the form of the invention 10 illustrated in Figs. 1 to 4) is shown as comprising a contact-bar 5 and rails or guides 6 and 7, the bar 5 and the rails 6 and 7 being preferably mounted upon an insulated block E, conveniently fastened to a plate e, attached 15 to the back of the retaining-box E'. The box E' is shown as closed by a cover E'', which may be removed to permit access to be had to the mechanism therein. The contact-bar 5 is of suitable conducting material, such as 20 brass, copper, or the like; but the rails 6 and 7 are mainly of non-conducting material, such as hard rubber, fiber, or the like. At the top of the rail 7 is mounted a gate 8, that is shown as pivoted at 9 (see Figs. 2 and 4) to 25 the upper end of the rail 7. The top edge of the gate 8 is shown as beveled, so as to bear squarely upon the inclined upper part of the rail 6, and the gate 8 is forced normally toward the upper part of the rail 6 by a suitable 30 spring. I have shown for this purpose a coil-spring 10, (see Fig. 4,) that passes around the pintle 11 of the gate, one end of the coil-spring bearing against the gate and the other end of the coil-spring engaging the 35 rail 7. The rail 6 and the rail 7 are each provided with one or more contact-plates, the number and arrangement of which will depend upon the number of floors for which the switch is designed and the particular floor adjacent 40 which the switch is located. The detailed views Figs. 2, 3, and 4 of the drawings show the switch that controls circuits for the first and second floors in the form of apparatus shown in Fig. 1, and in this switch the rail 6 is provided with a contact-plate F, while the 45 rail 7 is shown as provided with two contact-plates G and G'.

Within the box E' of each switch are mounted suitable guide-rods 15, that serve to guide 50 the cross-head II, each cross-head having arms h formed with openings, through which pass the guide-rods 15. Each of the cross-heads II is formed with two holes, within which are set the tubular bushings 20, of insulating material, each bushing 20 having fitted therein a bearing-sleeve 21. (See Fig. 4.) One of the bearing-sleeves 21 has pivotally mounted therein the journal 22 of a contact-arm K, while the other bearing-sleeve 21 has 55 journaled therein the bearing-arm 22 of a similar contact-arm K', the arms K and K' having their free ends provided each with a contact brush or finger k and k'. The cross-head II is formed with threaded openings 60 adapted to receive set-screws 23, that serve to securely retain the insulating-bushings 20 and sleeves 21 in position. The contact-

finger k of the arm K is adapted to ride against the contact-bar 5, while the contact-finger k' of the bar K' is adapted during its upward 70 movement to ride against the rail 6 and contact-plate F and at the extreme of its upward movement to pass outside the gate 8 and then upon its down movement to ride against the outer face of the gate 8 and the outer face of the rail 7. The contact-arms K and K' are connected together by a coil-spring K², the ends of which engage the screw-posts h², fixed to the arms K and K', and this spring K² serves to hold the contact-fingers k and k' 80 in bearing with the rails 5, 6, and 7 and serves also for the passage of current between the contact-arms. The cross-head II is connected to the shifting cable Y' by means of a clip h², (see dotted lines, Fig. 2,) so that the cross-head moves in correspondence with the car B of the elevator-shaft.

In Figs. 5, 6, and 7 of the drawings is shown one of the push-button boxes D, designed for any floor intermediate the top and bottom floors of the building, and this push-button box is therefore provided with an "up" button M and a "down" button M'. It will be readily understood, however, that for the bottom floor of the building the push-button box 90 will contain but a single "up" button, while for the top floor of the building the push-button box will contain a single "down" button M', and, except as hereinafter noted, the construction of the push-button boxes for the 95 top and bottom floors will be the same as that illustrated in the drawings. Within the push-button box D (shown in Figs. 5, 6, and 7) are mounted two pairs of magnets O and O', these 100 magnets being held between the plates 30 and 31. The poles of the magnets O extend through the plate 31, that is of insulating material, and upon the side of the plate 31 are fixed the bars 32, 33, and 34, also of insulating material. The armatures O² of the magnets are pivotally supported by the pins o, that 105 project into the end bars 32 and 34 and the central bar 33, as shown. The central bar 33 is shown as a T-shaped bar, the laterally-extending ends of which bar have fixed theron 110 the contact-plates 35 and 36, while between these contact-plates 35 and 36 is arranged a central contact-plate 37, held in place by a binding-post screw 38. The plates 35 and 36 are connected by wires 39 with the coils 115 of the magnets O and O'. To each armature O² is connected a brush 40, of spring metal, the arms 41 and 42 of which are adapted to contact with the contact-plates 35 and 37. On each armature also is mounted a block 43, 120 of insulating material, to which block is fastened a shifting arm 44, that projects outwardly, as shown in Fig. 7, and has its free end inclined or curved and formed with the shoulder 45. Beneath each arm 44 extends 125 a plate-spring 46, that is attached to the bar 32, (see Fig. 6,) this spring serving to hold the arm 44 and the corresponding armature 130 in the position shown in full lines at Fig. 7

of the drawings. The plate 30 at one end of the magnets O and O' is formed or provided with lugs 50, to which are pivoted the ends of the button-levers 52 and 53, each of these levers having a bifurcated free end, between the arms of which is set a block 54, of insulating material. The levers 52 and 53 are forced normally against their corresponding buttons M and M' by a spring-plate N, that is attached to the front edge of the plate 31 by a screw n, the free ends of the spring-plate N engaging the levers 52 and 53 and serving to thrust them outward. The bifurcated ends of each of the levers 52 and 53 receive the free end of the corresponding arm 44, (see Fig. 7,) and each of the levers 52 and 53 is provided with a pin 57, adapted to bear upon the inclined edge of the arm and ride over the shoulder 45 thereof.

The mechanism last described is designed to operate as follows: When one of the push-buttons—M, for example—is forced inward it, will cause a corresponding inward movement of the lever 52, thereby forcing the pin 57 and its lever to ride along the inclined edge of the arm 44, thus moving this arm and the armature O², connected therewith, toward the magnets O and causing the pin 57 to engage with the shoulder 45, thus holding the lever 52 in its shifted position against the force of the plate-spring N. This movement of the armature O² will be sufficient to cause the arms 41 and 42 of the brush 40 to touch the contact-plates 35 and 37 and establish passage of current at such points. As soon, however, as the circuit is completed by the switch mechanism, (in manner to be hereinafter described,) thereby causing the passage of current through the magnets O, the armature O² will be drawn into contact with the pole of the magnets O, and the pin 57 will thus be released from engagement with the shoulder 45 of the arm 44, thereby permitting the spring N to throw the lever 52 to the normal position seen in Fig. 7.

Having thus shown the construction of the switch mechanism and the push-button mechanism, the arrangement of the electric circuits wherein these parts are placed will next be described.

From a conveniently-located battery P extends the wire p, from which branch wires p' p² p³ p⁴ lead to the binding-post 38 of each of the push-button boxes D, and from the pair of magnets O leads a wire 60, a branch 61 of which connects with the contact-plate F of the switch adjacent one of the elevator-shafts, while a similar branch 61^a connects with the corresponding contact-plate F of the switch at the adjacent elevator-shaft. It will be understood, of course, that if the elevator-shafts are more numerous and more switches are employed the number of branch wires from the wire 60 will be correspondingly increased. The contact-bar 5 of the switches (used in connection with the left-hand elevator-shaft illustrated in Fig. 1) is shown as

permanently connected by branch wires 64 and 64^a with the wire 65, that leads to one terminal of the incandescent lamp b within the elevator-car B, and from the opposite terminal of this lamp a wire 66 leads back to battery P.

From the foregoing description the operation of parts thus far defined will be seen to be as follows: The elevator-car B will be assumed to be at the ground-floor of the building, and it will be assumed that the contact-plate F will be arranged at such position upon the rail 6 that the finger k' of the contact-arm K' will touch the lower part of the contact-plate F at such time, so that the operator of the car will be given a signal one floor in advance of the floor at which he is to stop. If now a party on the second floor desiring to go up presses inward the "up" button M, the contact-arms 41 and 42 of the plate 40 will be brought to bear against the contact-plates 35 and 37. Current will then pass as follows: from battery P by wire p and branch wire p² to contact-plate 37, (see Fig. 6,) thence by arm 42, brush 40, and arm 41 to contact-plate 35, thence through magnets O, by wire 60 and branch wire 61, to contact-plate F, (see Fig. 2,) by contact-finger k', (assumed to be at such time in contact with the lower part of plate F,) by arm K' and coil-spring K² to contact-arm K, by contact-finger k to contact-bar 5, by branch 64 and wire 65 to the incandescent lamp b, and from the lamp b, by wire 66, to battery. Hence it will be seen that the lamp within the car will be caused to burn, thus indicating to the operator that a passenger upon the second floor desires to be carried upward. It will be understood that as the car B moves upward a corresponding upward movement will be given to the cross-head H by the switch-cable Y', and after the car B has passed the second floor (having taken on the passenger) the finger k' of the contact-arm K' will pass from off the upper part of the contact-plate F and onto the insulating-rail 6. Passage of current will then be interrupted and the signal-light within the car will cease to burn. The cross-head H will continue to travel upward in correspondence with the movement of the car B until the car reaches the top of the elevator-shaft, about which time the contact-finger k' of the arm K' will pass through the gate 8, which will close as the contact-arm K' passes beyond it.

On the down movement of the elevator and corresponding down movement of the cross-head H the contact-finger k' of the arm K' will ride against the side of the rail 7. By reference to Fig. 2 of the drawings it will be observed that the rail 7 is provided with two contact-plates G and G'. The contact-plate G is set at such position that the contact-finger k' of the arm K' will pass onto the upper part of the plate G at the time that the elevator is about at the third floor of the building, and the length of the plate G' is such that the con-

- tact-finger k' will pass from off this plate about the time that the elevator-car passes in its downward movement beyond the second floor of the building. The contact-plate G of the switch C, that serves for the first and second floors of the building, is connected with the push-button box D at the second floor by a branch 71 from a wire 70, that is united to the wire 72 of the pair of magnets O'. (See Fig. 5.) Hence it will be seen that if a party on the second floor desires to ride down he will depress the "down" button M', thus causing the arms of the brush 40 of the magnets O' to close the circuit between the plates 36 and 37.
- 15 As soon as the contact-finger k' in its downward movement passes onto the contact-plate G circuit will be completed as follows: from battery P by branch wire p^2 , plate 37, brush 40, plate 36, magnets O', wire 70, and branch 71 to contact-plate G, thence by contact-arms K' and K to contact-bar 5, thence by branch wire 64 and wire 65 to the lamp within the car, and from said lamp by wire 66 back to battery. The passage of current through magnets O' will release the lever 53 and permit the spring end N to restore it and the push-button M' to normal position. The lamp b within the car will continue to burn until the contact-finger k' of the arm K' passes from off the contact-plate G, when circuit will be broken and the lamp within the car will cease to burn.
- 20 The contact-plate G' of the rail 7 serves for the first floor of the building and is connected by branch wire 75 with a wire 76, that leads from the push-button box D of the first floor. Inasmuch as this push-button box D is located on the first floor, it will not be provided with a set of "down" magnets or any "down" button, but will be furnished simply with an 25 "up" button and magnets corresponding to the button M and magnets O, hereinbefore described, together with suitable parts coöperating therewith. Hence it will be seen that if the "up" button of the push-button box on the first floor be depressed current will pass from battery P by wire p and branch wire p' to contact-plate 37, thence through brush 40 to plate 45, thence through the magnets O by branch wire 76 to wire 75 to contact-plate G', thence through contact-arm K', wire K², and contact-arm K to rail 5, and thence by branch 30 64 and wire 65 to lamp b, and thence by wire 66 back to battery. The contact-plate G' is of such length that the finger k' of the arm K' will pass onto the upper part of this plate at the same time that the downwardly-moving car B nears the first floor, and the arm will remain upon the plate until the car leaves the first floor in its upward movement.
- 35 The switch mechanism for the third and fourth floors is the same as that hereinbefore described, except for the arrangement of the contact-plates. In the switch for the third and fourth floors the rail 6 will have its contact-plate F arranged at a higher point upon the rail and the upper end of the rail will be formed with a contact-plate G³, (see Fig. 1,)

so that as the car nears the top floor the contact-finger of the arm K' will pass onto this plate G³ and will remain upon this plate until the car in its downward movement passes onto the gate 8 and the rail 7. Hence when the car is near or at the top floor the "down" button of the top push-button box D will cause current to pass to the signal-lamp of the car in the following manner, viz: from battery P by wire p and branch wire p' to plate 37 of the push-button box, thence through brush 40 to plate 36, thence by wire 39 to the magnets O', thence by wire 70 and branch wire 80 to contact-plate G³, thence through contact-arm K', wire K², and contact-arm K to contact-bar 5, thence by wire 64^a to wire 65, thence to the lamp b, and from this lamp by wire 66 back to battery. The switch for the third and fourth floors will have contact-plates corresponding to the plates F and G, above described; but these contact-plates will be arranged at positions upon the respective rails 6 and 7 at higher points upon the rails, the contact-plate F being connected by branch wire 61 to a wire 60, leading from the pair of magnets O of the push-button box at the third floor, while the contact-plate G is connected by a branch 40 wire 81 with a wire 82, leading from the pair of magnets O' of said push-button box.

By reference to Fig. 1 it will be seen that the switch mechanism for the elevator-shaft A' is the same as that hereinbefore described, suitable cross connections being employed to electrically connect the switches, so that when a push-button upon any floor is depressed it will set the switches for each elevator-shaft. Thus in Fig. 1 it is seen that 100 the wire 70 not only connects by branch wire 80 with the contact-plate G² of the nearest switch, but the wire 70 also extends across to the opposite elevator-shaft and is furnished with a branch 83, leading to the contact-plate 105 G² upon the corresponding switch of said shaft. In like manner also the wires 60 and 82, that lead from the push-button box of the third floor, extend to the opposite elevator-shaft and are connected by branch wire 61^a 110 and 82^a with the proper contact-plates of the switch at such shaft. So, also, the wires 60 and 70, leading from the push-button box of the second floor, are connected by branch 115 wire 60^a and 70^a with the corresponding 120 switch of the elevator-shaft A'. Hence it will be seen that when a push-button is depressed the switches at each elevator-shaft are set in order to cause the signals to appear in the first car that may approach the floor from 125 which the signal is given. While I have shown the cars B and B' as provided with signal-lamps, it is manifest that any other form of visual or audible signal may be used instead of a lamp.

130 In Fig. 8 of the drawings I have shown not only signal-lamps within the cars, but have shown indicator-lanterns upon the several floors of the building in order that as a car

approaches a floor in upward or downward direction the corresponding lantern will be illuminated, and the switch mechanism is so modified as to control the passage of current both for signaling the operator of the car and for lighting the indicator-lanterns at the proper times. In this form of my invention each elevator-shaft is provided at each floor with a switch C^2 , the construction of which is shown in detail in Figs. 9 and 10 of the drawings. The first floor of the building is shown as provided with a single indicator-lantern L , having displayed thereon the words "First car up," and the top floor of the building is shown as provided with an indicator-lantern L^2 , having displayed thereon the words "First car down," while the intermediate floors of the building are each furnished with two such lanterns L and L^2 .

The switch C^2 is a duplex switch, being designed to perform the double office of controlling the passage of current through the signal-lanterns L and L^2 and through the signal-lamps b and b' of the car. By reference to Figs. 9 and 10 it will be seen that each switch C^2 is inclosed within a box E' , as in the form of switch hereinbefore described, and upon the back of the box is mounted a plate e , carrying an insulating-plate E , to which are attached the contact-bars 5^a and the rails or guides 6^a and 7^a , belonging to one section of the switch, and the contact-bar 5^b and the rails or guides 6^b and 7^b , belonging to the other section of the switch. Referring to Fig. 9, it will be seen that the rail 6^a , which is of insulating material, is provided with a contact-plate G^4 and the rail 7^a is provided with a contact-plate G^5 , while the gate 8^a is shown as formed of conducting material. In like manner the rail 6^b is provided with two contact-plates G^6 and G^7 , while the rail 7^b is provided with a contact-plate G^8 , and, as shown, also the gate 8^b at the top of the rail 7^b is formed of conducting material. Suitable guide-rods 15, mounted within the box, carry a cross-head H , the arms of which slide upon the guide-rods, as in the construction hereinbefore described. The cross-head H has mounted thereon four contact-arms K^3 , K^4 , K^5 , and K^6 , that are supported upon the cross-head as in the hereinbefore-described construction, the pair of arms K^3 and K^4 being connected by a coiled wire k^2 , while the pair of contact-arms K^5 and K^6 are connected by a coiled spring-wire k^4 . The cross-head H is connected with the switch-cable Y' , as hereinbefore described, so that the cross-head shall move in unison with the corresponding elevator-car. The duplex switch shown in Fig. 9 of the drawings is that designed for the third floor of the building; but it will be understood that the duplex switches used for all floors between the top and bottom will be the same, except for the location of the contact-plates that are arranged in each switch in correspondence with the floor at which the switch is located. The construction of the

push-button box is the same as hereinbefore described.

Referring more particularly to the detailed views Figs. 9 and 10 of the drawings and to the switch and circuit shown at the third floor of the building and adjacent the elevator-shaft A , it will be seen that the push-button box D is connected with battery P by wire p and by branch wire p^6 , that leads with the plate 37 of the push-button box. From the upper set of magnets O of the push-button box leads a wire 90, that is connected by a branch wire 91 with the contact-plate G^4 of the switch C^2 . The contact-bar 5^a of this switch is connected by a suitable branch to wire 65 a , that leads to the signal-lamp b within the elevator-car B , and from the lamp b a branch wire 66 a leads to a wire 66 b , that connects with the battery P . Hence it will be seen that when a passenger upon the third floor desiring to go up depresses the "up" button M current will be caused to pass from battery P by wire p to plate 37 of the push-button box, thence by brush 40 and plate 35 to the upper pair of magnets O , thence by wire 90 and branch wire 91 to contact-plate G^4 , and as the contact-finger of the arm K^4 passes onto the contact-plate G^4 during the upward movement of the car current will pass from plate G^4 to contact-arm K^4 by wire k^2 to contact-arm K^3 and thence by contact-bar 5^a to wire 65 a , that leads to the lamp b within the car B . From lamp b current will pass by wire 66 a and wire 66 b back to battery P . Hence it will be seen that as the car in its upward movement approaches the third floor the signal-lamp b within the car will be caused to burn.

Each signal-lantern L and L^2 consists of a suitable globe or frame having an incandescent lamp therein, the terminals of the lamp being shown in the drawings, Fig. 8, as projecting at one side of the lantern. When the push-button M is depressed in manner hereinbefore described, current will be caused to pass not only through the signal-lamp of the car, but will also pass through the lantern L . The wire 90, leading from the push-button box, is connected by branch 90 a with one terminal of the lamp within the lantern L , and from the other terminal of said lamp a wire 92 leads to the contact-plate G^6 of the rail 6^b . The contact-bar 5^b is connected by branch wire 93 with the wire 94, that connects to wire 66 b , leading to battery P . Hence it will be seen that as the car in its upward movement approaches the third floor (the "up" button having been depressed as above described) current will pass from the push-button box by wire 90 and branch wire 98 to lantern L , thence by wire 92 to contact-plate G^6 , thence to contact-arm K^6 , (which during the upward movement of the car will pass onto the contact-plate G^6), thence by coiled wire k^4 , contact-arm K^5 , contact-bar 5^b to branch wire 93 to wire 94, and by wire 66 b to battery. Hence it will be seen that when the "up"

button is depressed not only will the operator of the car receive a signal, but as the car approaches the floor the lantern L will be caused to burn, thus indicating the nearest car coming in upward direction. As soon as the car in its upward movement passes to such position that a corresponding movement of the cross-head H shall cause the contact-arm K⁴ to pass from off the contact-plate G⁴ and the contact-arm K⁶ shall pass from off the contact-plate G⁶ the signal-lamp within the car will cease to burn and the lantern L will also be extinguished. By reference to Fig. 9 it will be seen that the contact-plate G⁶ extends lower downward than the contact-plate G⁴, the purpose of this being to give to the waiting passenger a more extended signal than is necessary to be given to the operator in the car.

20 The lower or "down" magnets O' of the push-button box are connected by a wire 95 to a wire 96, from which a branch wire 97 leads to the contact-plate G⁵, and the contact-wire 95 leads to one terminal of the lantern L², from the opposite terminal of which lantern a wire 98 leads to the contact-plate G⁸, this plate G⁸ being in electrical connection with the gate 8^a, (in the third-floor switch,) which is also electrically connected with the contact-plate G⁷. Hence it will be seen that when the "down" push-button is depressed at the third floor current will be caused to pass from battery as follows, viz: by wire p to plate 37, by brush 40 to plate 36, to magnets O', to wire 95, to wire 96, to branch wire 97, to contact-plate G⁵, to contact-arm K⁴ by coiled wire k² to contact-arm K³, to bar 5^a, to wire 65^a, to lamp b within the car, and from lamp b by wire 66^a and wire 66^b to battery. The signal-lamp within the car B will thus be caused to burn. The same depression of the push-button M' will also cause current to pass from the magnets O' by wire 95 to one terminal of the lamp in the lantern L², and from the opposite terminal of said lamp current will pass by wire 98 to contact-plate G⁸, thence to arm K⁶, to coil-spring k⁴, to arm K⁵, to contact-bar 5^b, to branch wire 93, to wire 94, and thence by wire 66^b back to battery. The passage of current as last indicated will cause the lamp within the lantern L² to burn.

In Fig. 9 of the drawings the parts are shown in the position occupied at the time that the car in its downward movement has just passed 55 below the third floor of the building; but it is manifest that as soon as the car passes downward so far that the contact-finger of the arm K⁶ passes off the end of the rail 7^b the coil-spring k⁴ will draw the contact-arm to the left, 60 so that its finger shall bear against the rail 6^b, and in like manner when the contact-finger of the arm K⁴ passes off the end of the rail 7^a the spring k² will bring this contact-finger into bearing with the rail 6^a. The arrangement of the contact-plates G⁷ G⁸ and the gates 65^a and 8^b in the switch for the third floor (see Fig. 9) is such that after the car has left the

third floor and before it completes its upward travel the contact-finger of the contact-arm K⁶ will pass onto the contact-plate G⁷. Hence 70 passage of current through the lamp of the lantern L² will be established even before the car reaches the extreme of its upward movement, and as the car moves down the contact-finger of the arm K⁶ will move over the gate 75 8^a, causing current to continue to pass through the lamp of the signal-lantern until the contact-finger of the arm K⁶ passes from off the contact-plate G⁸, which will occur at the time that the car reaches the third floor in its downward movement. Inasmuch as the operator in the car does not need so long a signal in advance, the contact-finger of the arm K⁴, which controls the passage of current through the lamp in the car, will not pass onto the 85 gate 8^a (of conducting material) until the car has begun its downward movement from the fourth floor.

The push-button box for the first floor of the building will have but a single pair of 90 "up" magnets O, and the number and arrangement of contact-plates in the switch for this floor will be modified, since there is no down movement of the elevator-car from such floor. By reference to Fig. 8 it will be seen that the 95 rail 6^a of the switch C² is shown as having no contact-plates and that the contact-plate G⁵ of the rail 7^a is located at the extreme end of the rail. So, also, the contact-rail 6^b is shown as having a single contact-plate G⁶ and the rail 7^b is shown with a single contact-plate G⁸ located at its lower end, the contact-plate G⁸ being connected with the contact-plate G⁶ by a wire 99. From this construction it will appear that as the elevator-car on its down movement approaches the first floor the contact-finger of the contact-arm K⁴ will ride upon the contact-plate G⁵ and current will then pass from battery P through push-button box D, thence by wire 90 and branch wire 100 to contact-plate G⁵, thence by contact-arm K⁴ through wire k² to contact-arm K³, and thence to contact-bar 5^a, to wire 65^a, to signal-lamp b, and thence by wire 66^a and wire 66^b back to battery. The lamp b within the car B will thus be lighted to signal the operator just before the car reaches the first floor. As the car reaches the first floor the contact-arm K⁴ will pass from off the lower end of the contact-plate G⁵ and onto the rail 105 6^a, and as this rail is of insulating material the electric circuit will be broken and the lamp b will be extinguished. Manifestly, however, a contact-plate might be inserted in the lower part of the rail 6^a and be electrically connected with the contact-plate G⁵ if it should be desired to have the signal-lamp 110 continue to burn while the car is at rest upon the first floor. It will also be seen that when the push-button at the first floor is actuated 115 as last described current will also pass from battery P through push-button box D by wires 90 and 90^a through the lantern L, thence by wire 92 to contact-plate G⁶, thence by cross-

wire 99 to contact-plate G⁸, thence by arm K⁶, by wire k⁴, and by arm K⁵ to contact bar 5^b, thence by wire 93 to wire 94, and thence by wire 65^b back to battery. It will be seen, 5 therefore, that as the car nears the first floor the lantern L will be caused to burn, indicating to the passenger which of the several elevator-cars will be the first to go up. Just before the elevator-car B reaches the first floor 10 the contact-finger of the arm K⁶ will pass from off the contact-plate G⁸ and will be drawn by the spring k⁴ against the contact-plate G⁶, so that current will continue to pass through the lantern L so long as the car remains at the 15 first floor. As soon, however, as the car begins its ascent the contact-finger of the arm K⁶ will pass above the contact-plate G⁶, and current will thus be broken.

The top floor of the building is provided 20 with a push-button box D, having a single pair of "down" magnets O', and is provided with a single signal-lantern L². The switch for the top floor of the building is modified, as clearly shown by Fig. 8 of the drawings. 25 In this switch the rail 6^a is provided with a single contact-plate G⁴ at its upper end, and the contact-rail 6^b will also be provided with a contact-plate G⁷ at its upper end similar to the plate shown in Fig. 9 of the drawings. 30 For the top-floor switch, however, the rails 7^a and 7^b need not be provided with contact-plates. When the push-button at the top floor is actuated, current will be seen to pass as follows: from battery P by wire p to push-button box D, thence by wire 90 and branch wire 91 to contact-plate G⁴, thence (as the car nears the top floor) by contact-arm K⁴, wire k², and contact-arm K³ to contact-bar 5^a, thence by wire 65^a to lamp b within the car, 35 and thence by wires 66^a and 66^b back to battery. Current will also pass by wire 90^a to lantern L², thence by wire 98^a to contact-bar G⁷, thence to contact-arm K⁶ by wire k⁴, to contact-arm K⁵, to plate 5^b, thence by wire 93 40 to wire 94, and thence by wire 66^b back to battery. When the car reaches the top floor, the contact-finger of the contact-arm K⁴ will pass through the gate 8^a and the contact-finger of the contact-arm K⁶ will pass through 45 the gate 8^b (said gates being of insulating material in the top-floor switch) and the passage of current through the signal-lamp b of the car will be broken; but the contact-finger of the arm K⁶ will continue to rest upon the plate G⁷, and current will continue to pass 50 through the lantern L² so long as the car B remains at the top floor.

The switch mechanism at the several elevator-shafts is the same as already described, 60 and the several switches of the various elevator-shafts will be cross-connected, as indicated in the drawings and as will be readily understood by those familiar with this class of mechanism. It will be readily understood 65 that instead of signal lamps and lanterns, as above described, other styles of signals might be used, although the lamps and

lanterns are preferable. So, also, it will be understood that the details of the switch mechanism may be varied without departure 70 from the spirit of the invention and that such switch mechanism may also be advantageously used in other situations.

While in the preferred embodiment of the invention I employ two contact-arms, one 75 riding over a contact-surface and in constant electrical connection therewith and the other riding over rails or guides and at intervals engaging with contact-plates, still it is manifest that the broad purpose of the invention 80 may be attained without adopting this specific construction. So far as I am aware my invention presents the first instance of a switch in which there is a movable contact-arm adapted to be shifted back and forth in 85 combination with means for guiding said arm in different paths during its movements in opposite direction, so that the contact brush or finger of said contact-arm shall make different contacts when moving in one direction 90 from the contacts made by it when moving in the opposite direction. The precise manner in which said movable contact-arm has its constant connection made with the electric circuit is therefore not essential, although 95 preferably it is accomplished as hereinbefore described. So, also, while it is preferable to provide one of the rails with a gate or flexible end portion to guide the contact-arm I do not wish the invention to be understood 100 as restricted to this precise means for guiding the contact-arm.

Having thus described my invention, what I claim as new, and desire to secure by Letters Patent, is—

105

1. An electric switch comprising a movable contact-arm and means for shifting said arm back and forth in combination with means to engage the end of said contact-arm and so direct its movements in different paths, contact-plates arranged along said different paths of said contact-arm, and suitable means whereby said contact-plates and said contact-arm may be connected with the electric circuit. 110

2. An electric switch comprising a pivoted contact-arm, of means for shifting said arm back and forth in combination with guide-rails against which the free end of said arm will travel and a device adapted to engage 115 the free end of said arm for causing the same to travel along one of said guide-rails by a movement in one direction and along the other of said guide-rails while moving in the opposite direction, and suitable contact-plates 120 interposed in the path of travel of said arm. 125

3. An electric switch comprising a movable contact-arm and means for shifting said arm back and forth, in combination with guide-rails for said arm, one of said rails being 130 shorter than the other, means for directing the arm from one guide-rail to the other and suitable contact-plates arranged along the different paths of said contact-arm.

4. An electric switch comprising a movable contact-arm and means for shifting said arm back and forth, in combination with guide-rails for said arm, a gate whereby the path of travel of said contact-arm is changed from one guide-rail to the other, and suitable contact-plates arranged in the path of travel of said contact-arm.
5. An electric switch comprising a pair of contact-arms and means for shifting the same back and forth, in combination with a contact-bar with which one of said arms engages, plural contact-plates arranged to be engaged by the other of said contact-arms, and means for guiding said last-named contact-arm against different plates during its movements in opposite directions.
6. An electric switch comprising a contact-bar and plural contact-rails, a cross-head movable along said bar and rails, said cross-head being provided with a contact-arm adapted to ride along the contact-bar and with a second contact-arm adapted to ride on its upward movement against one of said rails and upon its downward movement against another of said rails, and one or more contact-plates arranged in the path of said second contact-arm.
7. An electric switch comprising a contact-bar, a contact-arm movable along said bar and having a finger or part engaging therewith, rails arranged adjacent said bar and a second contact-arm electrically connected with said first contact-arm, contact-plates arranged in the path of said second contact-arm, and a swinging gate whereby said last-named contact-arm is caused to pass from engagement with one of said rails into engagement with the other of said rails.
8. An electric switch comprising two movable contact-arms, a contact-bar of conducting material along which one of said arms will travel, plural rails along which the other of said contact-arms will travel, means for deflecting one of said contact-arms to cause it to pass from one rail to another, and suitable spring mechanism for holding said contact-arms in bearing with the contact bar and rails.
9. An electric switch comprising two movably-supported contact-arms and suitable means for reciprocating said arms, a contact-bar along which one of said arms will travel and two contact-rails along which the other of said contact-arms will travel, one of said rails being shorter than the other, a swinging gate for deflecting the contact-arm from one rail to the other and contact-plates in suitable number and arrangement along said rails.
10. An electric switch comprising two or more movable contact-arms, a support whereby said arms are carried back and forth, a contact-bar of conducting material against which one of said contact-arms will bear, plural rails against which the other of said contact-arms will bear and means at the upper ends of said

rails for engaging the free end of said last-named contact-arm in order to shift it and thus cause said arm to ride upon a different rail while moving in downward direction from the rail whereon it rides while moving in the upward direction and one or more contact-plates arranged in the path of said last-named contact-arm.

11. An electric switch comprising two or more contact-arms, a movable part whereby said contact-arms are carried and whereon they are pivotally mounted, a contact-bar along which one of said contact-arms will travel, plural contact-rails and means for causing the other of said contact-arms to travel along one of said rails in one direction and along the other of said rails in the opposite direction, and spring mechanism for holding said contact-arms in engagement with said contact-bar and said rails.

12. An electric switch comprising the combination with suitable guides, of a reciprocating cross-head, contact-arms pivotally mounted upon said cross-head, a contact-bar along which one of said contact-arms will move, plural rails provided with one or more contact-plates and suitable means for causing the other of said contact-arms to move along one of said rails in one direction and against the other of said rails in the opposite direction.

13. An electric switch comprising two independent contact-bars and two independent pairs of contact-rails provided with contact-plates, in combination with a cross-head mounted in manner free to move along said bars and rails and two independent pairs of contact-arms, one contact-arm of each pair being arranged to engage the corresponding contact-bar and the other contact-arm of each pair being arranged to bear against its corresponding guide-rails.

14. In a signaling apparatus for elevators, the combination with push-button or like circuit-controlling mechanism arranged along the elevator-shaft and with a signal upon the car, and with an electric circuit connecting said push-button or like mechanism and said signal, of a switch mechanism interposed in said circuit and comprising a contact-bar, a reciprocating contact-arm and means for shifting the same in unison with the elevator, a second contact-arm electrically connected with said first-mentioned arm and plural rails for guiding said second contact-arm, and contact-plates along said rails said contact arm and rails being arranged independently of the elevator-car.

15. In a signaling apparatus for elevators, the combination with a push-button or like circuit-controlling mechanism arranged along the elevator-shaft and with a signal upon the car and with a signal at the door of the elevator-shaft, of a switch mechanism comprising two independent contact-bars and two independent pairs of guide-rails, and a cross-head mounted to move along said contact-

bars and guide-rails and provided with two independent pairs of contact-arms, one arm of each pair being arranged to engage the corresponding contact-bar and the other arm of each pair being arranged to engage the corresponding pair of contact-rails, and electric circuits whereby said switch mechanism is connected to said signals and to said push-button mechanism.
